UNITED STATES PATENT OFFICE.

DEAN A. WALTERS, OF TOLEDO, OHIO, ASSIGNOR TO THE WILLYS-OVERLAND COMPANY, OF TOLEDO, OHIO, A CORPORATION OF OHIO.

CARBON-SCRAPING TOOL.

Application filed June 7, 1918. Serial No. 238,663.

To all whom it may concern:

Be it known that I, DEAN A. WALTERS, a citizen of the United States, residing at Toledo, in the county of Lucas and State 5 of Ohio, have invented certain new and useful Improvements in Carbon-Scraping Tools, of which I declare the following to be a full, clear, and exact description.

The present invention relates to a carbon 10 scraping tool and has for its object to provide a tool adapted to be inserted through a more or less restricted opening, such as the relatively small bore formed through the head of an internal combustion engine cylinder for receiving the spark plug; the tool being provided with shiftable knives movable to operative position within the engine cylinder, after being inserted through said opening, to effect the scraping of both 15 the piston and cylinder heads on the inner faces thereof.

A further object of the invention is to provide a carbon scraping tool comprising a guide or holder upon which is reciprocally mounted a rod for moving a pair of pivotally connected members from a normal aligned position upon the holder into angular relationship therewith, either or both of said pivotal members when in said angular 20 position serving as knives or scrapers for removing carbon from opposing surfaces between which the knives are adapted to operate.

Further objects, and objects relating to 25 economies of manufacture and details of construction, will definitely appear from the detailed description to follow:

I accomplish the objects of my invention by the devices and means described in the 30 following specification. My invention is clearly defined and pointed out in the appended claims.

A structure constituting a preferred embodiment of my invention is illustrated in 35 the accompanying drawings, forming a part of this specification, in which:

Fig. I is a sectional elevation through an internal combustion engine cylinder, showing the lower tool blade or knife in 40 operative position upon a piston within the cylinder.

Fig. II is a fragmentary sectional elevation, showing the upper tool blade or knife in operative position upon the inner surface 45 of the dome-shaped head of the cylinder.

Fig. III is an enlarged, detail, sectional view through the knife holder with the knives shown in normal position therein.

Fig. IV is an enlarged, detail view of the lower portion of the tool showing the knives 60 in expanded or operative position.

Fig. V is a transverse sectional view taken through the upper knife on line V—V of Fig. III, and

Fig. VI is a similar sectional view taken 65 on line VI—VI of Fig. III.

In the drawings, similar reference numerals refer to similar parts throughout the several views and the sectional views are taken looking in the direction of the little 70 arrows at the ends of the section lines.

Considering the numbered parts of the drawings, 1 represents the cylinder of an internal combustion engine upon which is mounted the dome-shaped head 2 carrying 75 the cup 3 into which the spark plug (not shown) is normally screwed.

In the preferred embodiment of the invention, I have shown the carbon scraping tool applied to a Knight sleeve valve motor 80 but it will be understood that the invention is readily applicable to other types of engines and I therefore do not wish to limit its use to the type shown or to any particular 85 type of internal combustion engine, or other fuel burning apparatus.

Mounted within the cylinder 1 are the inner and outer sleeves 4 and 5, respectively, the piston 6 being movable within the former to any desired position with respect to the 90 cylinder head when the carbon is to be removed from said piston by inserting the scraping tool within the cylinder and turning it after the knife has been moved to operative position.

In the preferred embodiment of the invention I provide a holder 7 which is preferably a tube in which is slidably mounted a rod 8. The rod is notched at its inner end as indicated at 9 to receive the knife or pivotal member 10 and is also provided with a pin 11 extending into an elongated slot 12 in the knife 10, said slot having convergently arranged sides 13 and 14 upon which the pin moves when the knife is actuated by movement of the rod, said knife being provided with a cutting or scraping edge 15, as shown in Fig. V. The knife 10 is pivoted at 16 to the inner end of the outer knife or pivotal member 17 which is provided with a cutting 100 edge 18. The knife 10 is pivoted at 16 to the inner end of the outer knife or pivotal member 17 which is provided with a cutting 105 edge 18. The knife 10 is pivoted at 16 to the inner end of the outer knife or pivotal member 17 which is provided with a cutting 110 edge 18.

or scraping edge 18, as clearly shown in Fig. VI. The knife or pivotal member 17 is pivoted upon the transversely disposed pin 19 of the tube 7, said pin being extended 5 through the elongated slot 20 formed in the outer end of the knife. By making the slot 20 of a greater length than the diameter of the pin, the curved or cutting edge of the knife will become more readily ad- 10 justed to the curved face 21 of the piston head during the operation of the tool, it being understood that the cutting edge of each of the knives will be shaped to fit the contour of the respective surfaces upon 15 which they are adapted to operate. Likewise the slot 14 of the knife 10 will permit adjustment of the latter upon the pin 11, so that the scraping or cutting edge of the knife will readily adjust itself to the curved 20 face of the cylinder head 2 when the rod is actuated to the position shown in Fig. II.

The knives of pivotally connected mem- 25 bers 10 and 17 are movable from normal po- sition within the tubular holder to operative 30 or angular position with respect thereto through the longitudinal slot 22 formed in said holder by sliding the rod 8 to the po- sition shown in Fig. I and during this period of operation the lower end of the knife 17 is 35 moved into the slot 23, at the base of which is an abutment 24 for limiting the movement of the knife upon its pivot, whereby said knife is held at the desired angular position with respect to the tubular holder.

35 A slot 25 is cut in the tube 7 opposite the upper end of the slot 22 to receive the back edge of the knife 10 as shown in Fig. III. The shoulder or abutment 26 which is formed at the bottom of the slot 25 is pref- 40 erably beveled or tapered inwardly and downwardly to receive the correspondingly inclined surface 27 upon the back edge of the knife 10 near the center thereof, which serves as a pivot point about which the knife 45 is rocked during its initial movement, there- by facilitating the movement of the knife both downwardly and outwardly to carry the pin 16 past the dead center and permit the knives and rod 8 to drop by gravity.

50 The pivotal movement of the knife 10 upon the shoulder 26 is further facilitated by the action of the pin 11 moving down upon the inclined surface 14 when the rod 8 is pushed inwardly, for the reason that said 55 pin is moved in a straight line, thereby throwing the upper end of the knife cut- wardly through the slot 25 and consequently moving the lower end in an opposite direc- tion through the slot 22, during which time 60 of course the knife is given both a pivotal and longitudinal movement. During this period of operation it will be understood that the beveled surface 27 of the knife also slides on the inclined shoulder 26 of the tube 65 7, as before stated, and that thereafter the

back edge of the knife will move upon said shoulder until said knife is brought substantially into operative position.

In order that the knives may be held more or less rigidly in their lowermost position to effect the best results when turning the same upon the surfaces to be scraped, I provide at the upper end of the knife 10 a slightly tapered surface 28 upon which the abutment or beveled surface 29 of the rod 8 rides when the tapered surface 30 of the knife passes below the shoulder 26 and into frictional engagement with the inner wall of the tube, as shown in Fig. II. By this means the upper end of the knife 10 is wedged between the 80 beveled surface 29 of the rod 8 and the inner surface of the tube and is thereby rigidly held in the desired position when operated.

The knife 10 is also provided with a beveled surface 31 reversely inclined with respect to 85 the surfaces 28 and 30 and which normally engages the beveled surface 29 of the rod, the latter serving to rigidly hold the knife in normal position.

The rod 8 is adapted to be reciprocated in 90 the tube by means of the thumb screw 32 movable in the slot 33, said screw serving also as a means for clamping or locking the rod upon the tube when the knives have been set in the desired operative position as well 95 as when in normal position.

The tube 8 is provided with a sleeve bearing 34 which is preferably shaped to snugly fit the spark plug cup 3, as shown in Fig. I, said sleeve serving to hold and steady the 100 tube 7 when the latter is rotated by means of the handle 35 at the outer end thereof.

The bearing is adapted to be locked in any desired position upon the tube by means of the thumb screw 36, as shown in Fig. I. 105

When it is desired to remove the tool from the cylinder or other receptacle into which it may have been projected, it is only necessary to loosen the thumb screw 32 and raise the rod until the parts assume the position 110 shown in Fig. III.

After the accumulated carbon has been scraped from the piston and cylinder heads, as above described, the same will be blown out through the exhaust ports 37 and 38 of 115 the sleeves 4 and 5, respectively, into the exhaust pipe 39 when the engine is started and thereby discharged from the cylinder.

I am aware that the particular embodiment of my invention, which I have here 120 shown and described, is susceptible of considerable variation without departing from the spirit thereof, and, therefore, I desire to claim the same broadly, as well as specifically, as indicated by the appended claims. 125

Having thus described my invention, what I claim as new and desire to secure by Letters Patent, is:

1. In a scraping tool, the combination with 130 a holder having an abutment thereon and a

- rod slidably mounted upon the holder of a knife pivoted upon the holder and a pivotal connection between said knife and said rod, said knife engaging said abutment when moved to operative position.
2. In a scraping tool, the combination with a tubular holder, of an operating member movable therein, and a pair of pivotally connected knives normally lying within the holder, one of which is pivoted upon the holder and the other directly upon said operating member said knives being moved from the tubular holder when actuated to operative position.
3. In a scraping tool, the combination with a tubular holder having a shoulder formed thereon of an operating member slidably mounted in the holder, and a pair of pivotally connected members, one of which is separately pivoted upon the holder and the other connected with said operating member, and adapted to pivot upon said shoulder when said members are moved to operative position.
4. In a scraping tool, the combination with a holder and an operating member movable thereon, provided with a beveled surface and a pair of pivotally connected members, one of which is pivoted upon the holder and the other upon said operating member, said beveled surface and said holder co-operating with said pivotal members to rigidly hold them in operative position.
5. In a scraping tool, the combination with a holder and an operating member movable thereon, of a pair of pivotally connected members, one of which is pivoted upon the holder and the other on said operating member, said operating member having an abutment thereon for forcing the pivotal member connected therewith into frictional engagement with the holder when said pivotal members are moved to operative position.
6. In a scraping tool, the combination with a holder and an operating member movable thereon, of a pair of knives pivotally connected at their inner ends, the outer end of one of said knives being pivoted upon the holder and the outer end of the other knife upon said operating member, said operating member having a beveled surface adapted to engage the knife pivoted thereon to force the same into frictional engagement with the holder when said knives are in operative position.
7. In a scraping tool, the combination with a holder and an operating member movable thereon, of a pair of shiftable members pivotally connected at their inner ends, one of which is pivoted at its outer end to the holder and the other directly to said operating member, the last mentioned shiftable member being provided with oppositely inclined beveled surfaces, one of which is adapted to frictionally engage the holder when said members are in operative position, said operating member having an abutment thereon adapted to ride upon the other of said beveled surfaces for the purpose of rigidly holding said shiftable members in operative position.
8. In a scraping tool, the combination with a tubular holder and an operating member movable therein, of a plurality of pivotally connected members, and means for pivotally connecting one of said members with said holder and the opposing member with said operating member, the member connected with the operating member being limited in its movement with respect thereto by engagement with the inner wall of the tubular holder when moved to operative position.
9. In a scraping tool, the combination with a holder and an operating member movable thereon, of a pair of pivotally connected scrapers, one of which is pivoted upon the operating member and the other upon the holder, said holder being provided with an abutment for limiting the movement of the scraper pivoted thereon.
10. In a scraping tool, the combination with a holder having an abutment thereon of a rod slidably mounted upon the holder provided with an inclined surface, and inner and outer pivotally connected members, said inner member being movably mounted upon said rod and adapted to be actuated thereby from a normal aligned position with respect to the rod into angular relationship therewith and adapted to be forced into engagement with the holder by said inclined surface, and said outer member being pivoted upon said holder and adapted to be actuated by the inner pivotal member into engagement with said abutment.
11. In a scraping tool, the combination with a holder, of a rod slidably mounted thereon, inner and outer pivotally connected members, each of which is provided with a knife edge, said inner member being pivotally connected to said rod and said outer member being loosely connected with said holder and pivotally connected to said inner member.
12. In a scraping tool, the combination with a holder provided with an abutment and having a shoulder forming a pivot point thereon, a rod slidably mounted upon the holder, and inner and outer pivotally connected members, said inner member being adapted to be actuated by said rod about said pivot point and said outer member pivoted upon said holder and arranged to engage said abutment when moved to operative position.
13. In a scraping tool, the combination with a tubular holder having a shoulder thereon, a rod slidably mounted in the

holder and a knife pivotally connected to and adapted to be actuated by the rod into and out of the holder upon movement of the rod in opposite directions and to pivot upon 5 said shoulder when moving out of the holder.

14. In a scraping tool, the combination with a tubular holder and a rod slidably mounted in the holder, of a pair of pivotally 10 connected members, one of which is pivoted upon the rod and the other directly upon the holder, said members being adapted to normally lie within the tubular holder and arranged to be projected through a slot formed 15 therein by movement of the rod.

15. In a scraping tool, the combination with a tubular holder and a rod slidably mounted in the holder, of a pair of pivotally connected members, one of which is pivoted 20 upon the rod and the other directly upon the holder, said members being adapted to normally lie within the holder and arranged to be projected through a slot formed therein by movement of the rod, and means for 25 locking the rod upon the holder in various positions of adjustment thereon.

16. In a scraping tool, the combination with a tubular holder and a rod slidably mounted therein, a scraping tool normally 30 lying within the holder and arranged to be projected through a slot formed therein upon movement of the rod in one direction and to be returned to normal position when the rod is moved in an opposite direction, 35 and means extending through a slot in the holder for sliding and locking the rod within the holder.

17. In a scraping tool, the combination with a tubular holder and a rod slidably 40 mounted therein, a pair of pivotally connected knives normally lying within the holder and arranged to be projected through a slot formed therein upon movement of the rod in one direction and to be returned to 45 normal position when the rod is moved in an opposite direction, and a thumb screw projecting through a slot formed in the holder into engagement with the rod for moving and locking the same within said holder.

50 18. In a scraping tool, the combination with a tubular holder and a rod slidably mounted therein, a knife within the holder pivotally connected directly to said rod and a link connection between the knife and 55 holder loosely pivoted upon the latter, said knife and link being adapted to be projected from the tubular holder through a slot formed therein by movement of the rod.

60 19. In a scraping tool, the combination with a tubular holder, of a rod slidably mounted therein, and a knife loosely pivoted upon the rod, a second knife pivotally connected with the first and loosely pivoted upon the holder, said knives normally lying

within the holder and adapted to be projected through a slot formed therein, said holder being insertable in an internal combustion engine cylinder through an opening formed in the head thereof for removing carbon from the inner surface of said head. 65 70

20. In a scraping tool, the combination with a tubular holder, of a rod slidably mounted therein, an operating member for said rod extending through a slot in the side wall of the tubular holder, a knife pivoted 75 upon said holder and a knife actuating member having one end pivoted upon said knife and the other upon said rod, said knife and actuating member normally lying within the holder and adapted to be projected therefrom through a slot formed therein, said tubular holder having a member adapted to engage in the spark plug socket of an internal combustion engine. 80

21. In a scraping tool, the combination 85 with a tubular holder and a bearing upon which the holder is rotatably mounted, of a rod slidably mounted in the holder, a member pivoted upon the holder, and a knife pivoted between said member and said rod 90 and adapted to be projected into and out of the holder through a slot formed therein.

22. In a scraping tool, the combination with a tubular holder and a rod slidably mounted therein, of a knife operatively connected with said rod normally lying within the holder and adapted to be projected therefrom through a slot formed therein upon movement of the rod in the direction of the knife said holder having a shoulder 100 thereon intermediate the ends of the knife serving as a pivot about which the knife is moved during its initial movement when actuated from normal position.

23. In a scraping tool, the combination 105 with a tubular holder and a rod slidably mounted therein, of a knife operatively connected with said rod normally lying within the holder and adapted to be projected therefrom through a slot formed therein upon 110 movement of the rod in the direction of the knife said holder having an inclined shoulder thereon and said knife having an inclined surface adapted to engage said shoulder, said shoulder serving as a pivot 115 about which the knife is moved during its initial movement when actuated from normal position.

24. In a scraping tool, the combination with a tubular holder and a rod slidably 120 mounted therein, of a member operatively connected with said rod normally lying within the holder and adapted to be projected therefrom through a slot formed therein upon movement of the rod, said member being provided with an inclined surface on the back edge thereof an abutment upon the holder engaging said inclined surface 125

and co-operating with the same to effect a pivotal movement of said member when actuated from normal position whereby it is projected from the holder and a knife pivotally connected with said member and with said holder.

25. In a scraping tool, the combination with a tubular holder having a shoulder thereon and a rod slidably mounted therein, 10 a knife normally lying within the holder and adapted to be projected therefrom through a slot formed therein, said knife being provided with an inclined surface upon its upper end and a correspondingly inclined 15 surface on its back edge near the center thereof normally engaging said shoulder, and a fixed pin carried by said rod and projecting into engagement with the first mentioned inclined surface.

20 26. In a scraping tool, the combination with a tubular holder having a shoulder thereon and a rod slidably mounted therein, a knife within the holder having an inclined surface on its back edge normally engaging 25 said shoulder, said knife being provided with a reversely inclined surface at its upper end adapted to be forced into engagement with the inner wall of the tube when the knife is moved to operative position, and 30 a pin upon said rod extending into a slot formed in the upper end of the knife, said slot having convergently arranged sides with which the pin co-operates in moving the knife into and out of the holder.

35 27. In a scraping tool, the combination with a tubular holder having a shoulder thereon, and a rod slidably mounted therein, a knife within the holder having an inclined surface on its rear edge normally engaging 40 said shoulder, a pin upon the rod extending into a slot formed in the upper end of the knife, the latter being provided with adjacent convergently arranged surfaces, one of said surfaces being engaged by 45 a beveled surface on the rod when the knife is in normal position and the other by said beveled surface when the knife is moved to

operative position through a slot formed in the wall of the holder.

28. In a scraping tool, the combination 50 with a tubular holder having a shoulder thereon and a rod slidably mounted therein, a knife within the holder having an inclined surface, intermediate its ends normally engaging said shoulder, said knife being provided at one end with a correspondingly inclined surface normally engaging a beveled surface formed on said rod and having a reversely inclined surface adjacent the last mentioned surface, and means pivotally 55 connecting the knife with said rod, said connecting the knife with said rod, said shoulder serving as a pivot about which the knife is actuated during its initial movement when operated by said rod, said reversely inclined surface being movable into 60 engagement with the inner wall of the tubular holder when the knife is moved to operative position.

29. In a scraping tool, the combination 70 with a tubular holder and a rod slidably mounted therein, of a pair of knife blades having cutting edges shaped to conform to the upper surface of the piston head and the lower surface of the cylinder head respectively, said knife blades being adapted 75 when in collapsed position to be retained within the tubular holder and when in extended position to project therefrom whereby they may be brought into engagement with the upper surface of the piston head 80 or the lower surface of the cylinder head to remove carbon therefrom.

30. In a scraping tool, the combination 85 with a tubular holder and a rod slidably mounted therein, of a pair of knife blades 85 connecting said rod and holder and adapted when in collapsed position to be positioned in longitudinal alignment within the tubular holder, the said knife blades being adapted to be forced into operative position outwardly of the holder upon relative movement of said rod and holder.

In testimony whereof, I affix my signature.
DEAN A. WALTERS.
